UNITED STATES PATENT OFFICE

166,159

STACKING MEMBER OR SIMILAR ARTICLE

Jerome Greben, San Diego, Calif.

Application September 25, 1951, Serial No. 16,734

Term of patent 14 years

(Cl. D58—12)

To all whom it may concern:

Be it known that I, Jerome Greben, a citizen of the United States, residing at San Diego, in the county of San Diego and State of California, have invented a new, original, and ornamental Design for a Stacking Member, or Similar Article, of which the following is a specification, reference being had to the accompanying drawing, forming part thereof, in which:

Fig. 1 is an isometric view of a stacking member, or similar article, showing my new design;

Fig. 2 is a side elevational view; and

Fig. 3 is a top plan view thereof.

I claim:

The ornamental design for a stacking member or similar article, substantially as shown.

JEROME GREBEN.
